UNITED STATES PATENT OFFICE.

ANDREW MORRISON, OF PITTSBURG, PENNSYLVANIA, ASSIGNOR TO
DILWORTH, PORTER & COMPANY, LIMITED, OF PITTSBURG, PENN-
SYLVANIA, A CORPORATION OF PENNSYLVANIA.

TIE-PLATE.

No. 852,284.

Specification of Letters Patent.

Patented April 30, 1907.

Application filed July 24, 1906. Serial No. 327,472.

To all whom it may concern:

Be it known that I, ANDREW MORRISON, of Pittsburgh, Allegheny county, Pennsylvania, have invented a new and useful Tie-Plate, of which the following is a full, clear, and exact description, reference being had to the accompanying drawings, forming part of this specification, in which—

Figure 1 is a top plan view of one form of my improved tie plate; Fig. 2 is a side view of the same; and Fig. 3 is an end view.

My invention relates to anti-rocking tie-plates of the class described and claimed in my Patent No. 622,965, dated April 11th, 1899, in which the plate is provided with thinner extensions projecting laterally from its side edges beyond the rail bearing surface, and is designed to provide such a plate with a shoulder or abutment which can be readily rolled, and which requires but a minimum amount of metal in its formation.

In the drawings, the numeral 2 designates the plate which is formed on its under side with downwardly-projecting lateral flanges 25 and the intermediate flange 4.

5 indicates the reduced lateral extensions of the plate which provide for a maximum tie-bearing surface, these extensions being at each side of the rail-bearing portion 6.

30 7 designates the rail-seating shoulder which preferably extends entirely across the rail-bearing surface 6 near one end of the plate and terminates at the edges of such surface, the outer ends of the shoulder being substantially in line with the outer sides of the flanges 3. This shoulder may, however, be

of less length, but in any case it should extend for more than half the length of the rail-bearing surface.

8 designates spike holes, one of which intersects the shoulder 7, and the other of which is formed through the body portion of the plate.

The advantages of my invention consist in the provision of an anti-rocking tie-plate, 45 having a shoulder of substantially the length of the width of the rail-bearing surface of the plate, but of less length than the width of the tie-bearing surface, which not only facilitates the making of the plate and shoulder, but reduces to a minimum the amount of metal required.

What I claim is:—

1. A tie-plate having longitudinal tie-engaging flanges, reduced extensions projecting 55 from its side edges beyond the flanges, and a transverse shoulder of less length than the width of the plate but extending across a major portion of the rail-bearing surface of the plate; substantially as described. 65

2. A tie-plate having longitudinal tie-engaging flanges, reduced extensions projecting from its side edges beyond its rail-bearing surface, and a transverse shoulder formed on the rail-bearing surface and terminating at the 65 edges thereof; substantially as described.

In testimony whereof, I have hereunto set my hand.

ANDREW MORRISON.
